UNITED STATES PATENT OFFICE.

PAUL HALDEMAN STEHLEY AND JAMES HENRY HULINGS, OF PARSONS, WEST VIRGINIA, ASSIGNORS OF ONE-THIRD TO FRAZER P. STEHLEY, OF KEYSER, WEST VIRGINIA.

PNEUMATIC APPARATUS FOR DENTISTS OR PHYSICIANS.

SPECIFICATION forming part of Letters Patent No. 730,714, dated June 9, 1903.

Application filed October 2, 1902. Serial No. 125,652. (No model.)

To all whom it may concern:

Be it known that we, PAUL HALDEMAN STEHLEY and JAMES HENRY HULINGS, citizens of the United States, residing at Parsons, 5 in the county of Tucker and State of West Virginia, have made certain new and useful Improvements in Pneumatic Apparatus for Dentists and Physicians, of which the following is a specification.

10 Our invention is designed to provide for the use of dentists, physicians, and others a compact and easily-portable apparatus for supplying under pneumatic pressure a stream of air, water, (either hot or cold,) medicaments, 15 antiseptics, &c., in a simple, convenient, and practical manner. Its chief uses will be for dentists for blowing chips from the drilling of teeth, the drying of root-cavities, and for cleansing root-cavities and other portions of 20 the mouth or gum, while for physicians it will be used for irrigating and cleansing wounds or the natural cavities of the body and for administering enema. It is also applicable for use by embalmers, chemists, and others.

25 It consists in a novel construction and arrangement of pneumatic reservoir for air in combination with a bottle or receptacle for medicaments and various pipe connections, tubes, and nozzles, whereby the apparatus is 30 made available for the various uses named in a simple and convenient way, as will be hereinafter described with reference to the drawings, in which—

Figure 1 is a perspective view of the exterior of the apparatus, and Fig. 2 a vertical section of the pneumatic chamber and its accessory parts.

In the drawings, A represents the pneumatic reservoir, which is made of copper or 40 brass and of about the proportions of an ordinary tea-kettle. It is round in outline, and in the center of its upper part it is formed with a depression A', extending nearly to the bottom, and entirely open at its upper end 45 and adapted to receive and form a retaining seat or nest for any one of a series of interchangeable bottles or receptacles B for containing water or other liquids.

In the side of the kettle A is fixed in in-

clined position an air-pump C, by which air 50 may be forced into the tank under considerable compression. This pump may enter either at the side or through the top, as may be desired. A screw-cap A² in the top of the kettle permits water or other liquid to be inserted into the kettle and the interior to be cleaned, if necessary.

The kettle is supported upon a detachable base B⁴, having a flanged ring to retain the bottom of the kettle, and legs, with screw-holes through the feet, by which it may be fixedly secured to a table or other support. A spirit-lamp L, a gas-burner, or other portable heater is designed to be placed beneath the kettle to heat its contents.

60 The kettle A is perfectly tight when cap A² is screwed down, and it is designed to receive and hold under pressure both a body of water and a supernatant cushion of air for various uses and which may be made available 65 either hot or cold, according as the heater is used or not.

From a nipple on the top of the kettle a flexible pipe b³ is connected to a bottle B, seated in the depression A'. This pipe connects with one of the connections b² of a cap-stopper B' and admits through a valve v the air-pressure of reservoir A to the interior of the bottle. Another pipe connection b' of this stopper connects inside the bottle with a 80 pipe b, extending to the bottom, and at a point outside the bottle communicates through valve v' with a flexible pipe B², extending any suitable distance and provided with a terminal nozzle B³. When the air-pressure from 85 the reservoir-kettle is admitted through pipe b³ onto the top of the water medicament or other liquid in the bottle, said liquid is forced up pipe b and out through the pipe B² and nozzle B³ and is directed by the hand of the 90 operator to the hollow tooth or any other part of the body. As the bottle B fits closely in the central nest or depression A' in the kettle, it will be seen that the contents of the bottle are subjected to a warm-water bath and may 95 be maintained at any desired temperature and at the same time may be retained in glass in an immaculately clean condition.

With the upper part of the kettle A there connects by a suitable thimble another flexible pipe E, provided with a terminal nozzle E', having a suitable valve to control the discharge, and through this pipe and nozzle a jet of air, either hot or cold, may be directed to any point—such, for instance, as is required to blow out drill-chips from a tooth or to dry out cavities.

- 10 D is an upright pipe fixed in the top of the kettle and depending to a point near the bottom of the same. This pipe through a stop-cock d on the outside of the kettle connects with a flexible pipe D', having a nozzle D² of 15 suitable shape for enema purposes, for irrigating wounds, or for washing out any cavity of the body. When the stop-cock d is opened, it will be seen that the pressure of air on the top of the water in the kettle forces the water 20 out in a stream through the pipes D and D' with any desired energy, dependent upon the pressure of the air-cushion stored up by the pump C in the kettle above the surface of the water.
- 25 P is a pop-valve, which may be set to blow off at any desired pressure. This may or may not be used; but when a heating appliance is used the expansion of an already stored-up cushion of air renders such relief-valve a desirable adjunct.

We are aware that apparatus for dental uses have been heretofore devised for supplying under pressure air and water, and we therefore only claim our novel construction 35 and arrangement of parts, which provide a

more simple, compact, and convenient apparatus.

Although the pump C is described for pumping air into the reservoir A, it is obvious that it may also be used for pumping any 40 form of gas and storing this under pressure for medical purposes.

Having thus described our invention, what we claim as new, and desire to secure by Letters Patent, is—

45 A pneumatic dental apparatus for supplying either a liquid or a gas under pressure, consisting of a reservoir-kettle having a pendent depression extending from the top to near the bottom and open at the upper end, 50 a detachable receptacle seated in said depression and having a stopper provided with a pendent tube extending to near the bottom and an external stop-cock, pipe, and nozzle communicating with said pendent tube, a second pipe connecting said detachable receptacle with the top of the kettle, an air-compressing device fixed to the kettle and discharging into the same, and two separate pipes, connecting with the kettle, one entering the top 55 of the kettle to carry off air or gas, and the other extending to near the bottom of the kettle to carry off water under the pressure of the supernatant air or gas substantially as and for the purpose described.

PAUL HALDEMAN STEHLEY.

JAMES HENRY HULINGS.
